CANDELABRA

Maximilien Simon, Los Angeles, Calif.

Application June 3, 1958, Serial No. 51,173

Term of patent 14 years

(Cl. D48—2)

Figure 1 is a side elevational view of a candelabra embodying my new design;

Figure 2 is a top plan view thereof;

Figure 3 is a vertical sectional view taken through the finial member shown on the top of the candelabra illustrated in Figure 1, and

Figure 4 is a slightly enlarged fragmentary view, partly in section, typical of one of the leaf-like elements of the finial member, the other side thereof being fluted in the same manner shown in this figure.

I claim:

The ornamental design for a candelabra, as shown and described.
